UNITED STATES PATENT OFFICE

2,415,485

ULTRA HIGH FREQUENCY OSCILLATOR
AND AMPLIFIERCecil E. Haller, Bloomfield, N. J., assignor to
Radio Corporation of America, a corporation
of Delaware

Application October 17, 1942, Serial No. 462,351

21 Claims. (Cl. 179—171)

1

My invention relates to electron discharge devices and associated circuits, particularly useful at ultra high frequencies.

In high frequency practice one of the important considerations involved, aside from the transit time of the electrons in electron discharge devices, is a choice of a suitable and appropriate circuit. Such a circuit should have

1. High Q
2. Sufficient mechanical dimensions
3. Low radiation
4. Low surge impedance lines in order to
  - (a) Prevent excessive line shortening, if possible, due to tube capacity.
  - (b) Aid in getting a balanced circuit
  - (c) Minimize the effect of stray capacities so that they do not become a troublesome item.
5. Convenient means of introducing the D. C. power and grid return at points in the circuit where no R. F. voltage exists.

In conventional tubes employed in conventional circuits, it is difficult if not sometimes impossible to obtain these desirable characteristics.

It is, therefore, an object of my invention to provide an electron discharge device and associated circuit particularly suitable for use at ultra high frequencies.

Another object of my invention is to provide a circuit particularly suitable for use with electron discharge devices designed for ultra high frequency use and provided with a plurality of leads for each of the electrodes.

Another object of my invention is to provide a stable high frequency oscillator for use at frequencies up to 1200 megacycles and more.

A further object of my invention is to provide such an oscillator in which undesired radiation is reduced to a minimum.

A still further object of my invention is to provide a combined oscillator and power amplifier utilizing an electron discharge device of the type described and which is compact and fully shielded.

Another object of my invention is to provide a circuit for use at ultra high frequencies but of ample mechanical dimensions, having high Q, and provided with convenient means for introducing electrode voltages at points in the circuit where no R.-F. voltages exist.

The novel features which I believe to be characteristic of my invention are set forth with particularity in the appended claims, but the invention itself will best be understood by reference to the following description taken in connection with the accompanying drawings in which Figure 1 is a top view with cover removed of an electron discharge device and associated circuit made according to my invention and used as an ultra high

2

frequency oscillator, Figure 2 is a longitudinal section taken along the line 2—2 of Figure 1, Figures 3 and 4 are schematic diagrams illustrating electrical equivalents of the device shown in Figures 1 and 2, Figure 5 is a schematic wiring diagram of the device shown in Figure 1 and its associated voltage sources, Figure 6 is a vertical section of a combined oscillator and amplifier made according to my invention, and Figure 7 is a schematic circuit diagram of the apparatus shown in Figure 6 and its associated voltage sources.

In accordance with my invention I utilize an electron discharge device particularly designed for ultra high frequencies and provided with pairs of oppositely extending electrode leads and supports which reduce tube inductance and capacity when used at ultra high frequencies. These leads permit utilization of novel circuit apparatus made according to my invention.

Referring to Figures 1 and 2, the electron discharge device utilized in accordance with my invention comprises an envelope 18 and contains a cathode 11, grid 12 and anode 13, the grid 12 and anode 13 being provided with oppositely extending leads and supports 14—14 and 15—15. The device is provided with cathode heater leads 16 and cathode lead 17 connected and disposed in a manner to be described.

The oscillator circuit comprises concentric co-extensive collars or ring-like members 18—19 which support a pair of electron discharge devices between them as illustrated, the collars being provided with clip-like engaging elements 14' and 15' for engaging the leads 14 and 15. Surrounding the electron discharge device and the oscillator circuit proper and acting as a shielding member is a drum-like member 20 provided with a closed bottom 23 and removable top 24. The ring members are supported from the member 20 by means of the insulating supports 21 and 22. Extending from the bottom of the shielding member 20 is a tubular extension 25 through which the cathode leads 26 and 27 extend, a conducting member 28 contacting these tubular members for tuning the same in a manner and for a purpose to be described. As illustrated the cathode heater leads extend through and are shielded by the elements 26 and 27, the cathode lead proper 17 being electrically connected to the outside of these tubular members.

To tune the circuit I provide a plurality of rotatable condenser elements 30, 31, 32 and 33, which extend between but are out of contact with the collar elements 18 and 19. Oppositely disposed elements 31 and 33 are supported on an arm 35 while elements 30 and 32 are supported on an arm 36. These arms are in turn supported by coaxial concentric shafts 37 and 38 connected to an electrical gear box 39 provided with a con-

ventional arrangement of gears whereby the turning of a knob 40 connected to the gear mechanism will cause condenser elements 30, 31, and 32, 33 to move away or toward each other as desired.

The member 20 is provided with aperture 45 through which the coupling loop 46 extends for taking energy from within the shielding member 20 to a load or a radiator.

The schematic circuit diagram shown in Figure 5 shows the electrical relationship between the various elements and the voltage sources. The anode collar 19 is connected through a choke 47 to a source of positive potential whereas the grid collar 18 is connected through a biasing resistor 48 to ground. The shielding structure comprising the elements 20, 23, 24, 25 and 28 are also grounded. The cathode heater voltage is supplied by means of transformer 49.

The collar members 18 and 19, which are closed loops, serve as inductances for the oscillator, whereas the natural capacity between these elements plus the capacity of the tuning condensers provide the capacity for a resonant circuit driven by the electron discharge devices 10. Proper positioning of the shorting disc 23 will adjust the impedance of the cathode lines so that they offer feedback impedance to R.-F. currents attempting to travel along the conductors 26 and 27, such that proper grid excitation is obtained.

In Figure 3 is illustrated somewhat schematically the collar-like elements 18 and 19 which have been developed into parallel strips with the grids and anodes connected to opposite strips. As there indicated the distance between the anode and grid connections, and between the ends of the line and between the anode elements is equal to a half and a quarter wavelength. In other words, the electron discharge devices are spaced a half wavelength from each other. With this arrangement the voltage loop appears at the point of anode connection and the node midway between the same. Thus the effect is that of closed loops each a half wavelength long, the equivalent circuit of two such loops being shown in Figure 4. The capacity 43 is that capacity represented by the electrode elements and the loops 41 and 42 represent the inductance of that part of the collars 18 and 19 between the electrode elements and the nodal point on the collars. It will be observed that the result is a resonant circuit which will oscillate if properly driven, that is if an alternating voltage is applied across the plates of the condenser 43 which is the function of the electron discharge devices. Energy from the plate circuit to the grid circuit to support oscillation is chiefly through the capacity coupling between the collar elements, the electron discharge devices acting in push-pull.

While normally the device is operated with the cover 24 in place, the cover may be removed and the screening member 20, 23 used as a reflector for focusing the radio beam in any desired direction.

In connection with the tuning elements 30, 31, 32 and 33, as these elements are moved closer to the electron discharge devices 10 the resonant frequency of oscillation of the oscillator is reduced and as the elements are moved farther away from the electron discharge devices the resonant frequency of oscillation is increased. Moving the element away from the device 10 is the equivalent of tapping a condenser across fewer and fewer turns of an inductor in an oscillator tank circuit, whereas in moving the elements toward the electron discharge device is

equivalent to including more and more turns of the inductor between the terminals of a condenser bridged across the inductor so that at the tube, it is the equivalent of placing the condenser across all of the turns of the inductor, thereby decreasing the resonant frequency of the circuit.

With an apparatus made according to my invention and utilizing tubes of the type described, and using a 5½ inch diameter outer copper cylinder and a 4 inch diameter inner copper cylinder, both 2½ inches wide and 20 mils thick, I have obtained a frequency of operation of about 830 megacycles. Under certain conditions of operation the apparatus has also been made to operate at 1224 megacycles. Oscillations will start at about 300 volts on the plate with a power output from 8 to 10 watts.

In the modification shown in Figures 6 and 7 my invention is applied to a combined oscillator and grounded grid power amplifier. In this arrangement the oscillator comprises the lower section in which tubes 10 are mounted between the concentric collar cylinders 18' and 19'. The grid leads are connected to member 18' and the anode leads to member 19'. The tubes and the cylinders are mounted within a shielding arrangement comprising cylinder 50 closed at the top and bottom by covers 52 and 51. Oppositely extending tubular members 53 and 54 surround the coaxial cathode lines 55 and 56 shorted by the elements 57 and 58 and closed by means of the insulating discs 59 and 60. The member 50 is divided into two compartments by means of transverse partition 61.

The upper compartment encloses the amplifier. It includes the tubes 10 mounted between the cylinders 62 and 63. The member 63 is electrically connected to the shielding casing 50. The cylinder 62 is connected to the anode leads and the cylinder 63 to the grid leads. Thus the grid in the amplifier is grounded on the shielding apparatus. The upper compartment is provided with the cathode lead tuning extensions 64 and 65 coaxial with and surrounding cathode leads 66 and 67, the tuning being accomplished by the shorting discs 68 and 69. The members 64 and 65 are closed by the insulating closure members 70, 71.

To couple the oscillator to the amplifier I provide a pair of coupling members 74 and 75 shielded against radiation by means of tubular elements 76 and 77, thus forming coaxial lines. The cathode lines are so turned as to present a variable capacitive reactance which may be adjusted so that proper excitation is obtained. The R.-F. field within the members 53 and 54 furnishes the necessary energy for the coupling loops 74 and 75 which in turn excite the space within the tubular members 64 and 65 for feeding energy to the cathode of the tubes in the amplifier. The circuit relationships and voltage sources are best shown in Fig. 7.

As shown a high positive voltage is supplied to the inner cylinder 19' through choke 81 in the oscillator and to the inner cylinders 62 through choke 80 in the amplifier. The cathodes are heated by means of the heating transformer 78, 79, 83 and 84. Energy may be taken from the amplifier by means of the coupling loop 73 extending through aperture 72 in the outer cylinder 50.

In operation the oscillator portion of the apparatus is made to function in the same manner as the apparatus shown in Figure 1. Energy from the cathode circuits 55, 53 and 54, 56 which

are tuned for proper grid excitation of the oscillator, is transferred by means of the coaxial lines and loops 74—76 and 75—77, which feed energy into the cathode circuit of the amplifier tube and the amplifier portion of the apparatus. Thus an R.—F. voltage is applied between the cathode and grid of the amplifiers within the upper portion of the member 50, controlling the flow of current to the anodes of the electron discharge devices and exciting the space between the collar member 62 and collar member 63, energy being taken from this space by means of coupling loop 73 extending through aperture 72 in member 50.

While I have indicated the preferred embodiment of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. An oscillator including a plurality of electron discharge devices, each of which has a grid and an anode, and a pair of concentric collar-like elements, one of said elements being connected to the grids of said electron discharge devices and the other of said collar-like elements being connected to the anodes of said electron discharge devices, said electron discharge devices being spaced around said collar-like elements.

2. An oscillator including a plurality of electron discharge devices, each of which has a grid and an anode, each grid and each anode being provided with a plurality of leads, and a pair of concentric collar-like elements, said electron discharge devices being oppositely disposed and spaced around said collar-like elements, all of the grid leads being connected to one of said collar-like elements and all of the anode leads being connected to the other of said collar-like elements.

3. An oscillator including a plurality of electron discharge devices, each of which has a cathode and an anode, each cathode and each anode being provided with a plurality of leads, and a pair of concentric collar-like elements, said electron discharge devices being oppositely disposed, all of the grid leads being connected to one of said collar-like elements and all of the anode leads being connected to the other of said collar-like elements, and means capacitively coupled between said collar-like elements and movable between said electron discharge devices.

4. An oscillator circuit for an electron discharge device having an elongated envelope and having grid and anode electrodes, said grid and anode electrodes each being provided with a plurality of terminal leads, said circuit including a pair of concentric collar-like elements of conducting material, said concentric collar-like elements being provided with registering apertures through which said electron discharge device extends between said collar-like elements with the elongated dimension of the envelope perpendicular to the axis of said collar-like elements, one of said collar-like elements being connected to said grid leads and the other collar-like element being connected to said anode leads for exciting said oscillator circuit.

5. An oscillator circuit for an electron discharge device having an elongated envelope and having

grid and anode electrodes, said grid and anode electrodes each being provided with a plurality of terminal leads, said circuit including a pair of concentric collar-like elements of conducting material, said concentric collar-like elements being provided with registering apertures through which said electron discharge device extends between said collar-like elements with the elongated dimension of said envelope perpendicular to the axis of said collar-like elements, one of said collar-like members being connected to the grid leads and the other collar-like element being connected to the anode leads for exciting said oscillator circuit, and hollow conducting means surrounding the concentric collar-like elements of conducting material.

6. An oscillator circuit for an electron discharge device having a cathode, grid and anode electrodes, said cathode, grid and anode electrodes each being provided with a plurality of terminal leads, said circuit including a pair of concentric collar-like elements of conducting material having equal lengths parallel to their axis, said collar-like elements being coextensive in a direction parallel to their axis, one of said collar-like members being connected to the grid leads and the other collar-like element being connected to the anode leads for exciting said oscillator circuit, and a hollow shielding conducting member surrounding the concentric collar-like elements of conducting material, and a tubular extension mounted on said shielding member, the interior of which opens into the interior of said shielding member, said cathode leads extending through said tubular extension and means in said extension for tuning said cathode leads.

7. An oscillator including a plurality of electron discharge devices, each of which has a cathode, grid and anode, the grid and anode of each of said devices each being provided with a plurality of terminal leads, a pair of concentric collar-like elements between which and through which said electron discharge devices extend, said electron discharge devices being oppositely disposed and spaced around said collar-like elements, the grid leads of said electron discharge devices being connected to one of said collar-like elements and the anode leads of the electron discharge devices being connected to the other of said collar-like elements.

8. An oscillator including a plurality of electron discharge devices, each of which has a cathode, grid and anode, the grid and anode of each of said devices each being provided with a plurality of terminal leads, a pair of concentric collar-like elements between which and through which said electron discharge devices extend and around which said electron discharge devices are spaced, the grid leads of said electron discharge devices being connected to one of said collar-like elements and the anode leads of the electron discharge devices being connected to the other of said collar-like elements, and a cathode lead for the cathodes of each of said electron discharge devices, and means for tuning said cathode leads.

9. An oscillator including a pair of electron discharge devices, each of which has a cathode, grid and anode, the grid, anode and cathode being provided with terminal leads, a pair of concentric collar-like elements between which and through which said electron discharge devices extend, said electron discharge devices being oppositely disposed, the grid terminal leads of said electron discharge devices being connected to one of said collar-like elements and the anode terminal leads

of the electron discharge devices being connected to the other of said collar-like elements, and shielding means surrounding said electron discharge device and said collar-like elements, and means extending from one side of said shielding means through which the cathode leads extend, and means within said extension for varying the effective length of said cathode leads for tuning the same.

10. An oscillator including a plurality of electron discharge devices, each of which has a cathode, grid and an anode, the grid, anode and cathode of each device being provided with terminal leads, a pair of concentric collar-like elements between which and through which said electron discharge devices extend, said electron discharge devices being spaced around said concentric collar-like elements, the grid terminal leads of said electron discharge devices being connected to one of said collar-like elements, and the anode terminal leads of the electron discharge devices being connected to the other of said collar-like elements, and shielding means surrounding said electron discharge devices and said collar-like elements.

11. An oscillator including a plurality of electron discharge devices, each of which has a cathode, grid and an anode, the grid, anode and cathode of each device being provided with terminal leads, a pair of concentric collar-like elements around which said electron discharge devices are positioned, the grid terminal leads of said electron discharge devices being connected to one of said collar-like elements, and the anode terminal leads of the electron discharge devices being connected to the other of said collar-like elements, said collar-like elements having a circumference equal to a multiple of half wavelengths of the operating frequency, the terminal leads of said electron discharge devices being connected at half wavelength intervals.

12. An oscillator including a pair of electron discharge devices, each of which has a cathode, grid and anode, each grid and anode being provided with a plurality of terminal leads, a pair of collar-like conducting members concentric with each other and provided with oppositely disposed apertures for receiving said electron discharge devices and supporting the same within said apertures, contacts on said collar-like conducting members adjacent said apertures for receiving said terminal leads, the terminal leads of said grids being connected to contacts in one of said collar-like conducting members, and the terminal leads of the anodes being connected to the contacts of another of said collar-like conducting members.

13. An oscillator including a plurality of electron discharge devices, each of which has a cathode, grid and anode, each grid and anode being provided with a plurality of terminal leads, a pair of collar-like conducting elements concentric with each other, the terminal leads on said grids being connected to one of said collar-like elements, and the terminal leads on the anodes being connected to another of said collar-like elements, a shielding means surrounding said electron discharge devices and said collar-like conducting elements, conducting means extending between but out of contact with said collar-like elements and movable between said electron discharge devices, and means supported by said shielding means for supporting and moving said conducting means between said electron dis-

charged devices for varying the resonant frequency of said oscillator.

14. An oscillator including a plurality of electron discharge devices, each of which has a cathode, grid and anode, said grids, anodes and cathodes being provided with terminal leads, a pair of collar-like conducting members concentric with each other, the terminal leads on said grids being connected to one of said collar-like members and the terminal leads on said anodes being connected to another of said collar-like members, a shielding casing surrounding said electron discharge devices and said collar-like conducting members, a first tubular member extending from said shielding casing, a plurality of smaller tubular members within and coextensive with the first tubular member, the cathodes of said electron discharge devices being of the filament type and provided with a center tap lead, the center tap lead of said cathodes being connected to the smaller tubular members, the other terminal leads of said cathodes extending through said smaller tubular members, and movable conducting means within said first tubular member slidably supported on said smaller tubular members for tuning the cathode leads.

15. An oscillator including a plurality of electron discharge devices, each of which has a cathode, grid and anode, said grids, anodes and cathodes being provided with terminal leads, a pair of collar-like conducting members concentric with each other, the terminal leads on said grids being connected to one of said collar-like members and the terminal leads on said anodes being connected to the other of said collar-like members, a shielding casing surrounding said electron discharge devices and said collar-like conducting members, a first tubular member extending from said shielding casing, a plurality of smaller tubular members within and coextensive with said first tubular member, the cathodes of said electron discharge devices each being provided with three leads, one of which is electrically connected to one of said smaller tubular members and the others of which extend through the smaller tubular member, and means for closing the end of the first tubular member.

16. An oscillator circuit apparatus for use with a plurality of electron discharge devices, each of which has a cathode, grid and anode, said circuit apparatus including a pair of collar-like conducting members concentric with each other, the anodes of said electron discharge devices being connected to one of said collar-like conducting members and the grids of said electron discharge devices being connected to the other of said collar-like conducting members, and a drum-like shielding member surrounding said collar-like conducting members, a tubular member extending from one side of said drum-like shielding member, the interior of said tubular member communicating with the interior of the drum-like shielding member, and a plurality of parallel elongated elements supported within said tubular member and extending within the drum-like shielding member, the cathodes of said electron discharge devices being connected to said parallel elongated members, oppositely disposed conducting means extending between but out of contact with said collar-like conducting members, means for rotatably supporting said conducting means from one wall of said drum-like shielding member, and means for rotating said supporting means to vary the position of said conducting means between said collar-like members.

17. An oscillator circuit apparatus for use with a plurality of electron discharge devices, each of which has a cathode, grid and anode, said circuit apparatus including a pair of collar-like conducting members concentric with each other, the anodes of said electron discharge devices being connected to one of said collar-like conducting members and the grids of said electron discharge devices being connected to the other of said collar-like conducting members, and a drum-like shielding member surrounding said collar-like conducting members, a tubular member extending from one side of said drum-like shielding member, the interior of said tubular member communicating with the interior of the drum-like shielding member, and a plurality of parallel elongated elements supported within said tubular member and extending within the drum-like shielding member, the cathodes of said electron discharge devices being connected to said parallel elongated members.

18. A combined oscillator and amplifier including a first group of electron discharge devices, each of which has a cathode, grid and an anode, the grids, anodes and cathodes being provided with terminal leads, a first pair of concentric collar-like members, the terminal leads of said grids being connected to one of said collar-like members and the anode leads on said electron discharge device being connected to the other of said collar-like members, hollow shielding means surrounding said electron discharge devices and said collar-like members, cathode terminal leads extending externally of said hollow shielding means, and conducting means surrounding said cathode terminal leads and extending from said hollow shielding means, a second group of electron discharge devices each of which has a cathode, grid and anode, said last grids, anodes and cathodes being provided with terminal leads, a second pair of concentric collar-like members, the grid terminal leads of said second group of electron discharge devices being connected to one of said second pair of collar-like members and the anode terminal leads of said second group of electron discharge devices being connected to the other of said second pair of concentric collar-like members and a hollow conducting member surrounding said second group of electron discharge devices and said second pair of collar-like elements, the cathode terminal leads of said second group of electron discharge devices extending externally of said hollow conducting member, and conducting means surrounding the cathode terminal leads of said second group of electron discharge devices, and extending from said hollow conducting member, and means for coupling the cathode leads of the two groups of electron discharge devices.

19. A combined oscillator and amplifier including a plurality of groups of electron discharge devices, each of which electron discharge devices has a cathode, grid and an anode, a plurality of pairs of concentric collar-like members one of said groups of electron discharge devices having its anodes connected to one of the collar-like members of one pair and its grids connected to the other of said collar-like members of said one pair, and another group of said electron discharge devices having its anodes connected to one of the collar-like members of another pair of concentric collar-like members and the grids connected to the other of the collar-like members of said other pair, and a hollow conducting means surrounding said concentric collar-like members.

and their associated electron discharge devices and having a partition for electrically shielding said pairs of collar-like members and their associated electron discharge devices from each other.

20. A combined oscillator and amplifier including a plurality of groups of electron discharge devices, each of which electron discharge devices has a cathode, grid and an anode, a plurality of pairs of concentric collar-like members, one of said groups of electron discharge devices having its anodes connected to one of the collar-like members of one pair and its grids connected to the other of said collar-like members of the same pair, and another of said groups of electron discharge devices having the anodes connected to a collar-like member of another pair and the grids connected to the other collar-like member of the last mentioned pair of collar-like members, and hollow conducting means surrounding said pairs of concentric collar-like members and their associated electron discharge devices and a partition extending across said hollow conducting means for separately enclosing each of said collar-like members and their associated electron discharge devices and means for coupling one pair of concentric collar-like members and their associated electron discharge devices with another pair of collar-like members and their associated electron discharge devices.

21. A combined amplifier and oscillator comprising a hollow drum-like conducting member and conducting means dividing said drum-like conducting member into two compartments, a pair of concentric collar-like members within one of said compartments, and electron discharge devices, each of which has a cathode, grid and anode, the grids being connected to one of said collar-like members and the anodes being connected to the other of said collar-like members, and a second pair of concentric collar-like members in the other compartment, and electron discharge devices, each of which has a cathode, grid and anode, the anodes being connected to one of said collar-like members of said second pair and the grids connected to the other of said collar-like members of said second pair, oppositely disposed tubular extensions supported on said drum-like member and communicating with the interior of said compartments and longitudinal coaxial conducting members positioned within each of said tubular extensions, said longitudinal members being connected to the cathodes of said electron discharge devices, and means for electrically coupling the longitudinal conducting members for feeding radio frequency energy from one compartment to the other.
